UNITED STATES PATENT OFFICE.

ARTHUR L. RYDER, OF PASADENA, CALIFORNIA.

COMBINATION SPARK GAP AND PLUG.

933,115.

Specification of Letters Patent.

Patented Sept. 7, 1909.

Application filed May 15, 1907. Serial No. 373,870.

To all whom it may concern:

Be it known that I, ARTHUR L. RYDER, a citizen of the United States, residing at Pasadena, in the county of Los Angeles and State of California, have invented a new and useful Combination Spark Gap and Plug, of which the following is a specification.

The object of this invention is to provide an improvement in spark plugs for internal combustion engines in which the operator of such engine may be able to at any time observe the working of the spark-plug, and whereby the intensity of the igniting spark inside the engine may be increased. This spark-plug is adapted to utilize in a cheap, strong simple and compact construction the principle of the double-jump-spark.

An object of the invention is to make provision for ready and accurate adjustment of the length of the spark-gap under the inspection of the operator.

The spark plug comprises conducting elements and insulating elements, some of which are well known and some of which are new. The conducting elements may be made of any conducting material well known in the art or any equivalent therefor, and the insulating elements may be made of any well known insulating material.

In constructing the spark plug as the same will be illustrated in the accompanying drawings, porcelain, fiber, glass, hard rubber, mica, asbestos, and other substances may be used for various insulating parts thereof and I do not limit the invention to any particular kind or kinds of material.

The accompanying drawings illustrate the invention.

Figure 1 is a view of the spark-plug detached. Fig. 2 is an axial section on line indicated by $\alpha^2-\alpha^2$, Figs. 1 and 3. Fig. 3 is a plan section on line $\alpha^3-\alpha^3$, Figs. 1 and 2.

1 is the usual hollow hexagonal body portion provided with the externally screw-threaded hollow stem 2 to screw into the engine-body, not shown, and also provided with the externally and internally screw-threaded collar 3 to receive the insulation 4 and the bushing or gland 5 which holds the same in place.

6 is a sleeve provided with screw-threads internally, to engage the external screw-threads of the collar 3, and also provided internally with a shoulder 7.

8 is a housing in the form of a tubular body of insulating material provided with

lateral sight openings 9 and with a central opening 10 arranged to accommodate the adjustable igniter-bar section 11 having a pointed end 12 extending into the cavity of the hollow body 8 and forming one point of the spark. This hollow body 8 is insulated from the gland 5 by the insulating-ring 13.

14 and 28 are nuts for binding the terminal of the wire 15.

16 indicates packing of insulating material as thin mica sheets to prevent moisture from entering the housing through the end of the hollow body or cap 8, and to form a cushion between nut 28 and the housing 8.

17 is an igniter-bar section terminating inside the cavity of the body 8 in a spark-point 18 located in proximity to the spark-point 12, the shank of said igniter-bar being enclosed in a vitreous body or insulating sleeve 19 provided with a shoulder 20 which rests on a suitable shoulder 21 provided on the interior of the hollow hexagonal body portion.

22 is an insulating ring.

23 is a stem extension of the insulated igniter bar section 17 and terminates in a spark-point 24 in proximity to spark-point 25 that may be formed as an extension of the screw-threaded end 2 of the hexagonal body 1.

The space between the points 24 and 25 forms the spark-gap by which the spark for igniting the charge in the engine cylinder will be formed.

26 is a sleeve forming a socket or seat for the igniter-bar 11, and is externally and internally screw-threaded and extends through the end of the cap or hollow insulating body 8, and is provided inside said body with a circular head 27. Said socket is secured in place by said nut 28 screwed on the sleeve 26 against the insulation 16, thereby clamping the socket formed by the sleeve 26 and the head 27 firmly in place. The nut 14 is

screwed onto the sleeve 26 to bind the conductor 15 firmly in place, the sleeve 26 serving as a binding-post. The internal igniter-bar-section 17 is provided with a shoulder 29 which engages the insulation 22 and said section 17 is provided at its inner end with a screw-threaded portion 30 onto which is screwed a nut 31, thereby firmly securing the igniter section 17 in the porcelain insulator 19.

32 designates a hollow cylindrical insulator of mica seated in the hollow insulating body 8 and forming a transparent insulation

around the head 27, the nut 31, the juxtaposed spark-points 12 and 18, and between the same and the openings 9, so that the spark-gap between 12 and 18 will be open to 5 the view of the operator. The igniter-bar section 11 is provided with a slot or kerf 33 to receive a screw-driver for adjustment. The operator can readily adjust the width of the spark-gap between points 12 and 18 by 10 simply turning the section 11.

34 designates a packing of asbestos between the enlarged portion 20 and the metallic hexagonal body 1 to hold the insulator 19 firmly in place against rattling and to prevent escape of gas around the sleeve 19.

By making the cap 8 of glass the need of the openings 9 might be dispensed with as also the hollow mica cylinder 32, the purpose of said mica and the openings 9 being 20 to allow the spark gap between 12 and 18 to be open to view while electrically insulated from the external air.

In practical use, in case of trouble with the igniting apparatus provided with this 25 form of spark-plug, the attendant can determine by inspecting the gap between the spark-points 12 and 18, whether the trouble is caused by fouling of the inner spark-points. If it is noted that the sparking occurs between 12 and 18 without causing ignition of the charge in the engine, this indicates that the trouble is inside the plug and can be remedied by unscrewing the plug and 30 cleaning the spark-points 24 and 25 if the same are found to be foul. In addition to this, the duplication of the gaps causes greater intensity of spark between the spark-points 24 and 25, as is well known in the art. In case of any breakage of the porcelain 35 member 19, or of injury to the packing of the plug, this may be remedied by unscrewing the sleeve 6 and thus gaining access to the interior of the plug. The replacing or readjusting of any of the parts can be 40 readily accomplished as is apparent from inspection of Fig. 2 of the drawings.

I claim:

1. A spark plug comprising a hollow externally screw-threaded body adapted to 50 screw into the engine-body and provided with an externally and internally screw-threaded collar and an internal shoulder, insulation within the hollow body, packing around the insulation, a gland screw-seated 55 within the collar against the packing to hold the insulation in place, a tubular body of insulation material around the upper end of the first insulation and having transverse openings, a transparent cylinder within the 60 tubular body and covering said openings, an internally screw-threaded sleeve screw-seat-

ed upon the external threads of the collar and having a shoulder holding the tubular insulating body in place, an igniter bar in the insulation within the hollow body and terminating in a point visible through said 65 openings, and a second igniter bar extending downwardly through the tubular body.

2. A spark plug comprising a hollow externally screw-threaded body adapted to 70 screw into the engine-body and provided with an externally and internally screw-threaded collar and an internal shoulder, insulation within the hollow body, packing around the insulation, a gland screw-seated within the collar against the packing to hold the insulation in place, a tubular body of 75 insulation material around the upper end of the first insulation and having transverse openings, a transparent cylinder within this tubular body and covering said openings, an internally screw-threaded sleeve screw-seated upon the external threads of the collar and having a shoulder holding the tubular 80 insulating body in place, an igniter bar in the insulation within the hollow body and terminating in a point visible through said 85 openings, and a second igniter bar extending downwardly through the tubular body, said second igniter bar being adjustable.

3. In a spark plug, a hollow body externally screw-threaded at its lower end for insertion into the engine-body and having an internal shoulder and provided with an upwardly-extending externally and internally screw-threaded collar, a body of insulation mounted in the hollow body and having shoulders, there being packing around the shoulders; a gland inserted 90 downwardly into the collar to hold the insulation body in place, a second tubular insulation body extending upwardly from around the upper end of the first insulation body, a sleeve screw-seated upon the collar and having a shoulder holding the second 95 insulation body in place, there being sight-openings through the second insulation body; a transparent cylinder within the second insulation body covering said sight-openings, an igniter bar extending upwardly 100 through the first insulation and an igniter bar extending downwardly through the second insulation, the points of the igniter bars being visible through the sight-openings, and the upper bar being adjustable.

In testimony whereof, I have hereunto set my hand at Los Angeles California this 9th day of May 1907.

A. L. RYDER.
